UNITED STATES PATENT OFFICE.

KENNETH HOWIE, OF NORRISTOWN, AND WILLIAM O. TAYLOR, OF LIMERICK, PENNSYLVANIA, ASSIGNEES TO WILDMAN MFG. CO., OF NORRISTOWN, PENNSYLVANIA, A CORPORATION OF PENNSYLVANIA.

STRIPING MECHANISM FOR KNITTING MACHINES.

Application filed November 26, 1920. Serial No. 426,564.

To all whom it may concern:

Be it known that we, KENNETH HOWIE and WILLIAM O. TAYLOR, citizens of the United States, and residents of Norristown, Pennsylvania, and Limerick, Pennsylvania, respectively, have invented certain new and useful Improvements in Striping Mechanism for Knitting Machines, of which the following is a specification.

10 In carrying out the invention, while the control of the changes in the feed of the yarns is initiated by electro-magnetic means, the power employed in effecting the changes is transmitted mechanically from 15 the line shaft, or other source of power, and preferably through a rotating part of the machine. Therefore, the work imposed upon the electro-magnetic means is comparatively slight, and the time during which 20 the electro-magnetic means is performing its work at each change of the yarn feed is of short duration.

In the drawings:

Fig. 1 is a side view of a part of a knitting machine with our invention applied thereto.

Fig. 2 is a plan view in the nature of a diagram of the electric-jacquard or pattern mechanism and the means for operating the same from a part of the knitting machine.

Fig. 3 is a plan view of part of a knitting machine with a part of the invention in place.

Fig. 4 is a detail plan view of a star wheel and cam device and the arm and rod operated thereby.

Fig. 5 is a vertical sectional view through a part of the controlling mechanism.

Fig. 6 is a detail view of a cam.

Fig. 7 is a detail view.

Fig. 8 is a diagrammatic plan view of the feed finger, presser cam and associated parts.

In these drawings 1 represents a part of the head of a knitting machine, this being supported from a base ring 2 by frame parts 3, only one of which is shown, the machine being of that type in which the cam ring is fixed and the needle carrier rotates. At 4 is indicated the revolving take-up ring, the take-up being omitted, as this forms no part of the present invention.

The invention is shown in connection with a spring needle machine of the type disclosed in application for Letters Patent

of the United States, filed Sept. 9, 1920, S. 55 #409,265, though it will be understood that the invention is not limited to this type of machine.

There may be any desired number of feeds. The machine shown has eight feeds. 60 The yarn fingers, one of which is shown at 5, are pivotally mounted. The immediate actuating mechanism for these yarn fingers may be the same as that described in the said application involving a cam denoted generally at 6, operated by a star wheel 7, which is shifted to different horizontal planes by a vertical shaft or stem 8 so that the arms of the star wheel will be located either in or out of the path of the 70 dogs 9, 10, travelling with the rotary knitting head. When the dogs operate the star wheel step by step, for one-half revolution, the yarn feed finger will be shifted in or out by the cam controlling the shaft 11 of the 75 yarn feed finger by a slide 12 and a toothed collar 13, as in the application referred to.

The vertical stem or shaft of the star wheel is depressed to vary the height of the star wheel by a bell crank lever 14 pivoted 80 to a bracket 15 fixed to the stationary cam ring 16 of the knitting head. A spring such as disclosed at 22 of our previous application raises the star wheel with its shaft.

This bell crank lever is operated by a rod 85 17 reaching in towards the vertical axis of the knitting head.

It is guided at its inner end in a part of a track ring 18, held against rotation by a post 19 to which it is secured by a screw. 90 This post 19 is at the axial center of the knitting head, and it depends from a bracket or arm 20 extending up from the fixed base 21 of the knitting head. In an eight feed machine there will be eight of these rods, 95 one for each feed. They are controlled by the following mechanism:

An oscillating ring 22 is mounted on the fixed track ring 18. This ring carries a series of armatures 23 pivotally mounted at 100 24 in ears on the oscillating ring and extending thence towards the axial center of the machine. These armatures underlie electro-magnets 25, and when any magnet is energized, its armature will be pulled up 105 and it will be arrested in substantially a horizontal position by coming against the head of a stud or pin 26. Its tooth or

projection 27 will then lie in the same horizontal plane with the tooth of a star wheel 28 and in position to engage said tooth and give the star wheel a quarter turn as a result of the movement of the oscillating ring carrying the armature with it on its stroke in the arrow direction α Fig. 3.

The turning of the star wheel, which is mounted by its shaft 29 in the fixed plate or bracket 18, will turn a cam 30 mounted on the lower end of the said shaft. This cam bears upon a pin 31 carried by an arm 32 pivoted at 33 to the underside of the plate 18. The end of the arm has a stud 33' adapted to bear on the end of the rod 17 and control the position thereof, so that when the high part 30' of the cam presses upon the pin the arm 32 will be turned to move the rod 17 radially outward to cause the bell crank lever 14 to depress the center stem 8 of the immediate controlling mechanism of the yarn feed finger. This will effect a change at this particular feed finger, and the parts will remain in this position until the next change is to be made, when the star wheel 28 at the central controlling mechanism will be given another quarter turn, thus turning the cam to carry its high part 30' away from the pin 31 and bringing its low part 30'' opposite the pin, which immediately moves into this low part under the pressure of the spring 34 and this will cause the projection 33' to recede from the end of the rod 17 and allow said rod 35 to recede under pressure of the spring 35 which lifts the center stem 8 of the star wheel 7, so that this star wheel will be lifted with the result that the position of the yarn feed finger will be changed by the travelling dogs 9, 10, operating upon the arms thereof, which have been brought into their plane of travel. The cam 30 has depressions or notches at its high and low parts and the pin 31 of the pivoted arm 32 falls into these notches and thus acts as a detent to prevent the cam from overthrowing, the said arm as before stated being under pressure of the spring 34. It will be seen that the step by step movement 50 of the cam 30 operates the arm 32 to push the rod 17 radially outward or allows the arm to be retracted by its spring to allow the said rod to move radially towards the center of the machine and at all times the arm acts to hold the cam against overthrow.

One oscillation or back and forth movement of the ring 22 takes place at each revolution of the knitting head and therefore all of the armatures perform a back and forth movement laterally in a horizontal plane for each revolution of the machine, and if any armature be raised by its magnet, the companion star wheel 28 will be operated one step by the tooth of

the armature contacting therewith. The ring 22 is oscillated by a rod 36 connected with a pin 37 depending from the oscillating ring through a slot 38 in the fixed bracket or track ring 18. The other end of the 70 rod is connected with an arm 39 fixed on a vertical rock shaft 40 suitably journaled in fixed frame parts and having an arm 41 fixed thereto at its lower end and extending under the take-up ring to be operated by a cam 42 secured by posts 43 to the under side of the rotating take-up ring 4. The oscillation of the ring 22 is comparatively short. The electro-magnets are supported by and depend from a plate 80 44 secured to the center post before described and the electric circuit connections are shown at 45, 46.

For controlling the energizing of the magnets in any prescribed order to make 85 the pattern, a jacquard mechanism is employed, consisting of an endless band of paper 47, or other non-conducting material provided with openings 48 disposed according to the pattern to be formed, it being 90 understood that one or more feeds will have one color of yarn and another feed or feeds will have another color of yarn, or more colors than two may be employed. The openings in the paper band, are arranged 95 in transverse lines. Some lines may have one opening and other lines two or more openings. The paper band is hung on a drum 49 having a surface of conducting material, such as brass, and the paper is fed 100 by teeth 50 on the drum, engaging openings near the margins of the paper band. Overlying the drum are a series of contact fingers 51 of brass, and in the present eight feed machine there are eight of these 105 contact fingers. Each has a stud or contact point adapted to pass through the openings in the paper band to make electric contact with the brass surface of the drum, and it will be clear that each contact finger cooperates with one lengthwise row of 110 openings in the band.

The drum is in circuit by the binding post 52 and contact spring 53, Fig. 1. The whole series of contact fingers or strips 51 115 is brought down upon the paper by rocking the block or bar 53' on which the fingers are mounted. This bar is rocked by an arm 54 depending from one of its journals. The bar is journaled in a bracket 55 attached to the frame of the machine.

The depending arm 54 is connected by a link 56 to a lever 57 pivoted to the fixed frame at 58 and having its lower end in the path of a cam bar 59 secured by brackets 60 125 to the take-up ring. When the contact fingers are lowered, and if a hole in the paper band has arrived in proper position beneath the corresponding finger, the contact point thereon will pass through the 130

opening and contact with the surface of the drum and a circuit will be closed through the arm and as this arm is in the circuit with one of the magnets, this will be energized, raising its armature, and, due to the movement of the ring 22, this raised armature will turn the star wheel 28 and the connections before described will be operated to change the position of the yarn feed finger. The electro-magnetic means merely control the armatures, and thereafter the armature, which is in movement, due to the motion of the oscillating ring 22, will mechanically operate the connections to change the feed. The work imposed upon the electro-magnetic means is therefore slight, while the work of operating the connections is performed by the power leading from the line shaft or other prime mover, which rotates the knitting head. As soon as the movement of the ring 22 in the arrow direction is completed, the circuit to the electro-magnet is broken and the armature falls so that it is in its low position when the ring 22 moves back to normal position in a direction reverse from the arrow α , Fig. 3.

For controlling the electric circuit in proper time in relation to the rotation of the knitting machine, a circuit breaker is employed, consisting of the contact members 61, 62, mounted on the insulating block 63 fixed to the fixed base 2 of the machine. This circuit breaker is closed by a cam 64 on the take-up ring 3 lifting the member 61 into contact with the other member 62. This cam is elongated and is in the form of a track or bar.

Its forward end has an incline at 65 to ride under and lift the lower contact member, which is in the form of a leaf spring, which, when the cam passes from beneath it, resumes its lowermost position by its own resiliency and thus opens the circuit. The timing of this circuit closer 61, 62 relative to the depressions of the circuit closing fingers or strips 51 will be clear from an inspection of Fig. 2.

The cam bar 59 which mechanically lowers these fingers is longer than the cam track 64 and reaches beyond it both in advance and towards the rear thereof, as a result of which the fingers 51 are lowered into contact with the brass drum (according to the disposition of the holes in the paper) before the circuit is closed at the contacts 61, 62 and hence there will be no sparking at the drum when the contact fingers 51 are lowered, and, on the other hand, it will be seen that the circuit is broken at 61-62 before the contact fingers 51 are lifted from the drum and here again sparking and damage to the paper strip will be avoided. In other words, the current is not supplied until after the contact fingers 51 have been

pressed down on the drum and they are raised only after the circuit is broken at 61-62.

The drum 49 is rotated step by step by a ratchet 66 on the shaft thereof, and a pawl 70 67. This pawl is pivoted to a slide 68 which is mounted and guided in the boxing 69 secured to the supporting bracket, the slide being moved forwardly by a lever 70, pivoted at 71 and connected by a pin 72 with 75 the slide. The end of the lever is in the range of a pin 73 on an arm 74 fixed to the vertical rock shaft 40.

The pawl slide is retracted by a spring 75 bearing on a head 76 of a rod 77 fixed 80 to the slide.

All three cams 42, 59 and 64 are carried by the rotary take-up ring 3.

A detent 78 engages a toothed wheel 79 on the shaft of the drum to prevent over-thrown.

Means are provided for cutting the yarn when raised out of work, this involving a cutting blade 80 (Figs. 5 and 7) pivoted at 81' at the lower end of post 19 and cooperating with a fixed cutter blade 81 secured to said post in any suitable way. The pivoted blade is held in open position by a spring 82, the upper end of which is fixed at 83 to the base of the head or ring 18. 95 The pivoted cutter blade is operated by a rod 84 pivoted thereto at 85 and operated when the ring 22 is operated. This rod is moved vertically by an arm 86 engaging therewith said arm being mounted on a rock 100 shaft 87 journaled in bearings 88. This shaft is operated by an arm 89 which is lifted by a wedge or cam member 90 carried by a cross piece 91 which is connected to the ring 22 by the depending posts 37, 37'. This cross piece, of course, moves with the ring and thus brings its wedge under arm 89.

This cutter is located at about the level of the knitting plane. In Fig. 7, the dotted line γ - γ indicates the upper lever of the knitting head.

The inactive yarns when cut are held by the yarn retaining finger 92, one for each feed, this retaining finger being pivoted at 115 93 to a bracket 94 which supports the loop, 95 across which the yarn rests and within which the retaining finger operates.

The means for automatically controlling the cam α which effects the pressing of the needle beards is the same as that described in the said application for preventing the fabric running off from the needle when the yarn is thrown out of feeding position. This means consists of a slide 12^a operated 120 by the cam 6 and bearing on an incline 12^a of the shank 12^b of the presser cam α . The shank is pressed by a spring 12^d. These parts are shown diagrammatically in Fig. 8. When the slide 12^a is moved to the left in 130

Fig. 8 by the cam 6 it will retract the presser cam to where it will not press the needle beards. This takes place when the cam 6 throws the yarn finger to its in-operative position of Fig. 8.

The mechanism just described for controlling the presser cam *a* is the same as that disclosed in our application above referred to.

10. We claim:—

1. In combination in a knitting machine, knitting instruments, a plurality of yarn feed fingers, electro-magnets one for each feed finger, armatures therefor, a support for said armatures having travelling movement, means for moving said support, connections leading to the yarn feed fingers for controlling the positions of the same, said connections being operated by the travelling armatures, when the latter are in a prescribed position relative to their electro-magnets and pattern means for controlling the energizing of the electro-magnets, substantially as described.

2. In combination in a knitting machine, knitting instruments, a plurality of yarn feed fingers, electro-magnets one for each feed finger, armatures therefor, a carrier for said armatures, having a back and forth movement, means for operating the armature carrier, connections leading to the yarn feed fingers for controlling the positions of the same, said connections being operated by the armatures travelling with the carrier when said armatures are in a prescribed position relative to their electro-magnets, and pattern means for controlling the energizing of the electro-magnets, substantially as described.

3. In combination in a knitting machine, knitting instruments, a plurality of yarn feed fingers, electro-magnets one for each feed finger, armatures therefor, a carrier for said armatures having a back and forth movement, means for operating the armature carrier, connections leading to the yarn feed fingers for controlling the positions of the same, said connections being operated by the armatures travelling with the carrier when said armatures are in a prescribed position relative to their electro-magnets, and pattern means for controlling the energizing of the electro-magnets, said armature carrier in performing its back and forth movement turning about an axis, substantially as described.

4. In combination in a circular knitting machine, a plurality of yarn feed fingers, one at each feed, a head arranged coaxially with the knitting head, movable carrier means turning about the axis of the head, electro-magnets, armatures therefor mounted on the carrier and controlled by said electro-magnets, pattern mechanism for selecting which of the electro-magnets are

to be energized, circuit connections, means for operating the carrier means, and connections leading to the feed fingers and arranged to be operated by the armatures moving with the carrier, when said armatures are in a prescribed relation to their electro-magnets, substantially as described.

5. In combination with a circular knitting machine, having a plurality of feeds, a carrier arranged coaxially with the knitting head, and turning about the axis of said head, electro-magnets supported above the carrier, armatures pivotally mounted on the carrier to swing vertically to and from the electro-magnets, means for turning the carrier, pattern means for selecting and energizing the electro-magnets, and means operated by the movement of the armatures with the carrier, when the armatures are in their elevated positions under the influence of the magnets said means rendering the feeds effective or ineffective, substantially as described.

6. In combination with a circular knitting machine having a plurality of feeds, an electro-magnet and armature for each feed, means for giving travelling movement to the armatures independent of their movement towards and from the magnets, pattern mechanism for selecting and energizing the electro-magnets in a prescribed order to attract their armatures, means for rendering the feeds effective or ineffective, operated by the armatures in their travelling movement, comprising star wheels to be operated by the armatures, cams operated by the star wheels, levers operated by the cams, and rods operated by the levers, substantially as described.

7. In combination with a circular knitting machine having a plurality of feeds, a rotatable member arranged coaxially with the knitting head, a reciprocating rod connected to said member for giving the same oscillating movement about the axis of the knitting head, a series of pivoted armatures carried by said rotatable member and movable vertically about their pivots, a series of electro-magnets, one for each armature, arranged about the axis of the rotatable member and in fixed position, pattern control means for energizing said electro-magnets in a prescribed order, star wheels arranged to be contacted by the armatures when in their elevated positions to be turned thereby in the travelling movement of said armatures with the rotatable member, and connections leading from the star wheels for rendering the feeds effective or ineffective, substantially as described.

8. In combination with a circular knitting machine having a plurality of feeds, a movable carrier, a plurality of armatures pivotally mounted on said carrier, means for oscillating the carrier, electro-magnets for ele-

vating the armatures, pattern control means for energizing the electro-magnets in a prescribed order, star wheels, a fixed support for said star wheels, said fixed support furnishing the supporting means for the movable armature carrier, cams on the shafts of the star wheels, arms pivotally mounted and operated by the said cams, and radially extending rods operated by the said pivoted arms for rendering the feeds effective or ineffective, substantially as described.

9. In combination with a circular knitting machine having a plurality of feeds, a controlling mechanism arranged coaxially with the knitting head, said controlling means comprising a mechanically operated member, electro-magnetic means at the controlling mechanism, connections extending from the controlling mechanism to render the several feeds effective or ineffective, said connections deriving their power from the power operated means of the controlling mechanism, and rendered effective or ineffective by the electro-magnetic means, and pattern mechanism 25 for controlling the electro-magnetic means in a prescribed order, substantially as described.

10. In combination with a circular knitting machine having a plurality of feeds, a take-up ring rotating with the rotary part 30 of the knitting head, a vertical shaft, means carried by the rotary take-up ring for operating the vertical shaft, controlling means for the feeds comprising a member operated from the said vertical shaft, connections 35 leading from the said controlling means to render the feeds effective or ineffective, electro-magnetic means for connecting the said connections with the power operated vertical shaft of the controlling mechanism, and pattern controlled means for energizing the 40 electro-magnetic means, substantially as described.

11. In combination with a circular knitting machine having a plurality of feeds, 45 connections rendering the same effective or ineffective, a power operated member at the axis of the knitting head, means for operating the said connections from the said power operated member, electro-magnetic means 50 for controlling the operation of said operating means, a rotary take-up ring rotating with the rotary member of the knitting head, a connection operated by the rotary take-up ring for operating the power member of the 55 controlling mechanism, pattern means for controlling the electro-magnetic means, and circuit breaking means controlled by the rotation of the take-up ring, substantially as described.

60 12. In combination with a circular knitting machine having a plurality of feeds, controlling mechanism for rendering said feeds effective or ineffective in a prescribed order, comprising a mechanically operated member and electro-magnetic means for ren-

dering the same effective or ineffective, a member rotating in unison with the rotary member of the knitting head, means on said rotary member for actuating the mechanically operated member of the controlling 70 mechanism, circuit connections leading to the said electro-magnetic means, pattern means operated from said rotary member and including circuit closers for the circuits of the electro-magnetic means, and a main circuit breaker with means on the said rotary member for operating the same, substantially as described.

13. In combination with a circular knitting machine having a plurality of feeds, 80 controlling mechanism for rendering said feeds effective or ineffective in a prescribed order, comprising a mechanically operated member and electro-magnetic means for rendering the same effective or ineffective, a member rotating in unison with the rotary member of the knitting head, means on said rotary member for actuating the mechanically operated member of the controlling mechanism, circuit connections leading to the 85 said electro-magnetic means, pattern means operated from said rotary member and including circuit closers for the circuits of the electro-magnetic means, and a main circuit breaker with means on the said rotary member for operating the same, substantially as described.

14. In combination with a circular knitting machine having a plurality of feeds, controlling mechanism for rendering said feeds effective or ineffective in a prescribed 90 order, comprising a mechanically operated member and electro-magnetic means for rendering the same effective or ineffective, a member rotating in unison with the rotary member of the knitting head, means 95 on said rotary member for actuating the mechanically operated member of the controlling mechanism, circuit connections leading to the said electro-magnetic means, pattern means operated from said rotary member and including circuit closers for the 100 circuits of the electro-magnetic means, and a main circuit breaker with means on the said rotary member for operating the same, substantially as described.

15. In combination with a circular knitting machine having a plurality of feeds, controlling mechanism for rendering said feeds effective or ineffective in a prescribed 110 order, comprising a mechanically operated member and electro-magnetic means for rendering the same effective or ineffective, a member rotating in unison with the rotary member of the knitting head, means on said 115

rotary member for actuating the mechanically operated member of the controlling mechanism, circuit connections leading to the said electro-magnetic means, pattern mechanism including a drum, a series of circuit closing fingers, means on the drum cooperating with said circuit closing fingers for closing the circuits to the electro-magnetic means, connections for operating the circuit closing fingers from the rotary member and a main circuit breaker operated from the rotary member, substantially as described.

16. In combination with a circular knitting machine having a plurality of feeds, controlling mechanism for rendering the feeds effective or ineffective in a prescribed order, comprising a mechanically operated member and electro-magnetic means for rendering the same effective or ineffective, a member rotating in unison with the rotary member of the knitting head, means on said rotary member for actuating the mechanically operated member of the controlling mechanism, circuit connections leading to the said electro-magnetic means, pattern mechanism including a drum having electric conductivity, a perforated band passing over said drum, a series of contact fingers to close the circuits to the electro-magnetic means through the perforations of said band, means operated by the said rotary member for depressing all of the circuit closing fingers, means operated by the said rotary member for giving the drum a step by step movement and for actuating the said mechanically operated member of the controlling mechanism, a main circuit breaker and means for operating the same from the rotary member, substantially as described.

17. In combination with a circular knitting machine, having a plurality of feeds, controlling means therefor including mechanically operating connections and electro-magnetic selective means, a rotary take-up ring moving in unison with the knitting head, and means carried thereby for actuating the mechanically operating connections and controlling the electro-magnetic selective means, substantially as described.

18. In combination with a circular knitting machine, having a plurality of feeds, controlling means therefor for rendering them effective or ineffective for knitting in a prescribed order, said controlling means including mechanically operated connections and electro-magnetic selective means, electric circuits to said electro-magnetic means, one for each feed, a plurality of circuit closers, for closing the circuits to the electro-magnetic means in a prescribed order to select the connections which are to be operated for controlling the feeds, and

means carried by a rotary member of the machine for controlling the operation of the circuit closers and the mechanically operated connections, substantially as described.

19. In combination with a circular knitting machine having a plurality of feeds, controlling mechanism therefor to render them effective or ineffective in a prescribed order, a rotary take-up plate, a cam thereon, connections actuated by the cam for operating a part of said controlling mechanism, power transmitting connections leading to the feeds, said controlling mechanism including electro-magnetic selective elements for connecting in a prescribed order the transmitting connections with the said cam operated connections, pattern means for energizing the selective elements in a prescribed order and a cam on the rotary take-up plate with connections therefrom for operating the pattern means, substantially as described.

20. In combination with a circular knitting machine, having a plurality of yarn feed fingers, a connection for each yarn feed finger for controlling the same, controlling means for said connections including mechanical power operated driving means, and electro-magnetic selective elements for selecting in a prescribed order the yarn finger connections which are to be operated by said driving means, and pattern means for energizing the electro-magnetic selective elements in a prescribed order, substantially as described.

21. In combination with a circular knitting machine having a plurality of feeds, a controlling connection for each feed, electro-magnetic selective elements, pattern mechanism for determining the order in which the selective electro-magnetic elements will be set for operating the said controlling connections, a rock shaft, a rotary take-up plate, a cam thereon for operating the rock shaft, means for operating the pattern mechanism from the rock shaft, and a connection from the rock shaft for giving the selective elements a travelling movement to actuate the selected yarn finger connections.

22. In combination with a circular knitting machine, having a plurality of feeds, a controlling connection for each feed, electro-magnetic selective elements, pattern mechanism for determining the order in which the selective electro-magnetic element will be set for operating the said controlling connections, a rock shaft, a rotary take-up plate, a cam thereon for operating the rock shaft, means for operating the pattern mechanism from the rock shaft, and a connection from the rock shaft for giving the selective elements a travelling movement to actuate the selected feed controlling con-

- nections, said pattern mechanism including circuit closers for closing the circuits to the electro-magnetic selective means and a cam on the take-up plate for controlling said 5 circuit closers, substantially as described.
23. In combination with a circular knitting machine, having a plurality of yarn feeds, a controlling connection for each feed, electro-magnetic selective elements, 10 pattern mechanism for determining the order in which the selective electro-magnetic elements will be set for operating the said controlling connections, a rock shaft, a rotary take-up plate, a cam thereon for 15 operating the rock shaft, means for operating the pattern mechanism from the rock shaft, and a connection from the rock shaft for giving the selective elements a travelling movement to actuate the selected 20 feed controlling connections, said pattern mechanism including circuit closers for closing the circuits to the electro-magnetic selective means and a cam on the take-up plate for controlling said circuit closers, a 25 main circuit breaker and a cam on the take-up plate for controlling the main circuit breaker, substantially as described.
24. In combination in a circular knitting machine, having a plurality of yarn feeds, 30 star wheels with connections between the same and the feeds, contact means travelling with the rotary member of the knitting head for operating said star wheels, means for adjusting said star wheels to bring different arms thereof into the plane of movement of the contact means, said adjusting means comprising a member arranged coaxially with the knitting head, armatures pivotally mounted on said member, means 35 for giving said member a travelling movement, electro-magnets, means for selectively energizing said electro-magnets to raise the armatures in a prescribed order and connections operated by travelling movement 40 of the armatures when raised for changing the position of the star wheels, substantially as described.
25. In combination in a circular knitting machine, having a plurality of feeds, star 45 wheels with connections between the same and the feeds, contact means travelling with the rotary member of the knitting head for operating said star wheels, means for adjusting said star wheels to bring different arms thereof into the plane of movement of the contact means, said adjusting means comprising a member arranged coaxially with the knitted head, armatures pivotally mounted on said member, means for giving 55 said member a travelling movement, electro-magnets, means for selectively energizing said electro-magnets to raise the armatures in a prescribed order and connections operated by the travelling movement of the 60 armatures when raised for changing the po-

sition of the star wheels, said last mentioned connections including a star wheel operated by contact of the armatures therewith, substantially as described.

26. In combination in a circular knitting 70 machine, having a plurality of feeds, a controlling mechanism arranged coaxially with the knitting head, and including a back and forth moving member, armatures pivotally mounted thereon, electro-magnets for elevating the armatures, connections operated by the armatures for controlling the feeds, a yarn cutter for severing the yarn when raised out of work and means for operating said yarn cutter from the back and forth 80 moving member, substantially as described.

27. In combination in a circular knitting machine, having a plurality of feeds, controlling mechanism for the feeds including an oscillating member and electro-magnetic 85 selective means with connections therefrom to the feeds, a vertical post supporting said controlling mechanism, a yarn cutter supported on said post, and means for operating said yarn cutter from the oscillating 90 member.

28. In combination in a multiple feed knitting machine, needles, a plurality of yarn feed fingers, one for each feed, means for changing the position of the yarn feed 95 fingers to be in or out of work, including in part pattern mechanism, selector mechanism controlled by the pattern mechanism for selecting which of the yarn feed fingers is to be changed, and connections actuated 100 by power automatically and operating through the selector mechanism for effecting the changes in the positions of the fingers, each of said feeds including means for automatically preventing the work from 105 running off from the needles when the yarn feed fingers are thrown out of operation, all the needles in passing an idle feed, simply holding their old loops.

29. In combination in a circular knitting 110 machine needles, a plurality of feeds disposed at separated points about the same, including yarn feed fingers to be thrown into and out of working position, selector mechanism disposed above and coaxially 115 with the knitting machine, and comprising selecting devices, one for each feed finger, connections, one for each selecting device to be operated or not operated by said device according to the position of the latter 120 and extending therefrom to the yarn feed finger it is to operate, pattern mechanism controlling the setting of the selecting devices in selecting position, and power operated connections for moving the selecting 125 devices to drive the selected connections leading to the feed fingers, each of said feeds also including means for preventing the work from running off from the needles when the yarn feed fingers are thrown out 130

of work, all of the needles, in passing an idle feed, simply holding their old loops, substantially as described.

30. In combination in a knitting machine, a plurality of feeds disposed at separate points about the same, and each including a movable yarn feed finger to be set in or out of working position, pattern mechanism, selecting devices controlled by the said pattern mechanism to change the position of the yarn feed fingers, to knit or not to knit, a carrier for the selecting devices having travelling movement, means for driving the said carrier, and connections leading to the several feed fingers from the selecting devices to change the position thereof, said connections being operable by the travelling selecting devices when the latter are set in selecting position by the pattern mechanism, but remaining idle when the selecting devices are not so set, each feed also including means for automatically preventing the work from running off from the needles when the yarn feed fingers are thrown out of operative position all the said needles, in passing an idle feed, then holding their old loops.

31. In combination in a knitting machine, a plurality of feeds disposed at separate points about the same, and each including a movable yarn feed finger to be set in or out of working position, pattern mechanism, selecting devices controlled by the said pattern mechanism to change the position of the yarn feed fingers, to knit or not to knit, a carrier for the selecting devices having travelling movement, means for driving the said carrier, and connections leading to the several feed fingers from the selecting devices to change the position thereof, said connections being operable by the travelling selecting devices when the latter are set in selecting position by the pattern mechanism, but remaining idle when the selecting devices are not so set, each feed also including means for automatically preventing the work from running off from the needles when the yarn feed fingers are thrown out of operative position, said traveling movement of the carrier being reciprocatory, all the said needles, in passing an idle feed, then holding their old loops substantially as described.

32. In combination in a knitting machine, a plurality of feeds disposed at separate points about the same, and each including a movable yarn feed finger to be set in or out of working position, pattern mechanism, selecting devices controlled by the said pattern mechanism to change the position of the yarn feed fingers, to knit or not to knit, a carrier for the selecting devices having travelling movement, means for driving the said carrier, and connections leading to the several feed fingers from

the selecting device to change the position thereof, said connections being operable by the travelling selecting devices when the latter are set in selecting position by the pattern mechanism, but remaining idle when the selecting devices are not so set, each feed also including means for automatically preventing the work from running off from the needles when the yarn feed fingers are thrown out of operative position, said travelling movement being oscillatory about the axis of the knitting head all the said needles, in passing an idle feed then holding their old loops.

33. In combination in a circular knitting machine, a plurality of feeds each including a yarn feed finger to be set in or out of working position, a plurality of selecting devices each comprising a member pivotally mounted to move in a vertical plane, a carrier for the selecting devices, means for moving the carrier, pattern mechanism, means controlled thereby for setting the selecting devices in prescribed positions, and connections operated by the selecting devices when set in selecting position and moved by the carrier for controlling the positions of the yarn feed fingers, each of said feeds also including means for causing all the needles, in passing an idle feed, to hold their old loops and thus preventing the work from running off when the yarn feed finger is thrown out of feeding position.

34. In combination in a circular knitting machine a plurality of feeds each including a yarn feed finger to be set in or out of working position, a plurality of selecting devices each comprising a member pivotally mounted to move in a vertical plane, a carrier for the selecting devices, means for moving the carrier, pattern mechanism, means controlled thereby for setting the selecting devices in prescribed positions, and connections operated by the selecting devices when set in selecting position and moved by the carrier for controlling the positions of the yarn feed fingers, each feed including means for preventing the work from running off when the yarn feed finger is thrown out of feeding position, said carrier being arranged coaxially with the knitting head and turning about the vertical axis thereof, substantially as described.

35. In combination in a circular knitting machine having a plurality of feeds disposed at separated points about the same, and each feed including a yarn feed finger movably mounted to be thrown into and out of feeding position, a series of selecting devices, one for each feed, means for giving a travelling movement to the selecting devices, pattern mechanism for setting the selecting devices in selecting position in a prescribed order, and connections extending

from the selecting devices to the yarn feed fingers to be operated by the selecting devices in their travelling movement to position the yarn feed fingers, each connection 5 including a star wheel to be operated by one of the selecting devices, a cam operated by the star wheel, and a rod operated from the cam for positioning the yarn feed fingers, each feed including also means for preventing 10 the work from running off when a yarn feed finger is thrown out of work.

36. In combination in a circular knitting machine, having a plurality of feeds with a shiftable yarn feed finger at each feed 15 adapted to be thrown into and out of work, a rotatable carrier member arranged coaxially of the knitting head, a reciprocating rod connected to said member for giving the same oscillating movement about the axis 20 of the knitting head, a series of selecting devices mounted on the carrier and movable vertically, means including pattern mechanism for moving the selecting members vertically in a prescribed order, star wheels 25 arranged to be contacted by the selecting devices in their travelling movement when the latter are in their selecting positions and connections leading from the star wheels for controlling the yarn feed fingers 30 at the feeds, each feed including means for preventing the work from running off the needles when a yarn feed finger is withdrawn, substantially as described.

37. In combination in a knitting machine, knitting instruments, a plurality of feeds, electro-magnets, one for each feed, armatures therefor, a support for said armatures having travelling movement, means for moving said support, means for rendering 40 the feeds effective or ineffective, operated by the travelling armatures when the latter are in a prescribed position relative to their electro-magnets, and pattern mechanism for controlling the energizing of the 45 electro-magnets, substantially as described.

38. In combination in a knitting machine, knitting instruments, a plurality of feeds, electro-magnets, one for each feed, armatures therefor, a support for said armatures having travelling movement, means for moving said support, means for rendering the feeds effective or ineffective, operated by the travelling armatures when the latter are in a prescribed position relative 50 to their electro-magnets, and pattern mechanism for controlling the energizing of the electro-magnets, said armature support having a back and forth movement.

39. In combination in a knitting machine, 60 knitting instruments, a plurality of feeds, electro-magnets, one for each feed, armatures therefor, a support for said armatures having travelling movement, means for moving said support, means for rendering the feeds effective or ineffective,

operated by the travelling armatures when the latter are in a prescribed position relative to their electro-magnets, and pattern mechanism for controlling the energizing of the electro-magnets, said armature support having back and forth turning movement about an axis. 70

40. In combination in a knitting machine, knitting instruments, a plurality of feeds, electro-magnets, one for each feed, armatures therefor, a support for said armatures having travelling movement, means for moving said support, means for rendering the feeds effective or ineffective, operated by the travelling armatures when the latter are in a prescribed position relative to their electro-magnets, and pattern mechanism for controlling the energizing of the electro-magnets, said armature support being arranged above and coaxially with the knitting head and having oscillating movement about the axis of said head. 80

41. In combination in a circular knitting machine having a plurality of feeds disposed at separated points about the same, a connection for each feed to render the same effective or ineffective to knit, controlling means for said connections including mechanical power operated driving means, and electro-magnetic selective elements for selecting in a prescribed order the feeds which are to be rendered effective or ineffective by said driving means, and pattern mechanism for energizing the electro-magnetic selective elements in a prescribed order. 90

42. In combination in a circular knitting machine, a support oscillating about the axis of the machine, armatures carried thereby, electro-magnets for controlling the position of the armatures, pattern mechanism for controlling the energizing of the armatures in a prescribed order, and connections operated by the armatures when in a certain position relative to their electro-magnets for controlling changes in the work produced. 105

43. In combination in a circular knitting machine, a carrier, power means for giving movement thereto, armatures movably mounted on the carrier electro-magnets for controlling the positions of the armatures, pattern mechanism for controlling the energizing of the electro-magnets in a prescribed order, and connections operated by the armatures when in a certain position relative to their electro-magnets for controlling changes in the work produced, substantially as described. 115

44. In combination in a circular knitting machine, a plurality of feeds disposed at separated points about the knitting head with means at each feed to be adjusted for rendering said feed active or inactive, operating connections leading to each of said means, a mechanical power operated mem- 125

ber common to all of said connections, devices carried thereby to transmit movement to said connections when set to contact therewith, electro-magnets for setting said devices in contacting position, and pattern mechanism controlling the energizing of said electro-magnets.

45. In combination in a circular knitting machine, a plurality of feeds disposed at 10 separated points about the same, and each including a movable yarn finger for moving the yarn to and from the needles, and a cam acting on the needles and adjustable to make the needles hold their old loops, 15 in passing the feed, connections extending towards the center of the machine for operating the yarn fingers and adjusting the cams, hit and miss members at the inner ends of said connections, one of which has traveling movement, for operating said connections, and pattern mechanism for selecting which connection will be operated and for 20 relatively adjusting the hit and miss members of the selected connection to operate the 25 same.

46. In combination in a circular knitting machine, a plurality of feeds disposed at separated points about the same, and each including a movable yarn finger for moving 30 the yarn to and from the needles, and a cam acting on the needles and adjustable to make the needles hold their old loops, in passing the feed, connections extending towards the center of the machine for operating 35 the yarn fingers and adjusting the cams, an oscillating carrier, members movably

mounted thereon to at times contact with and operate said connections, and at other times to miss them, and pattern mechanism for adjusting the said members in a 40 prescribed order into line with said connections for operating the same, substantially as described.

47. In combination with a circular knitting machine, needles, a plurality of feeds 45 spaced apart around the machine, including a yarn finger at each feed movable upwardly from its yarn feeding position to float the yarn to the interior of the machine, yarn retaining means at each feed arranged 50 on the inside of the needle row to receive the yarn when floated to the interior of the machine, a needle beard presser cam at each feed, mechanism for rendering the feeds idle by raising the yarn feed fingers and adjusting the presser cams, including a back and forth moving carrier having contact devices thereon, and connections operated by 55 said contact devices leading to the yarn feed fingers and cams, pattern mechanism 60 for setting the contact devices to hit or miss said connections, and cutter means at the center of the machine with means for operating it from the movement of said carrier, said cutter receiving and cutting the yarn 65 when floated to the interior of the machine by the lifting of the yarn feed finger, substantially as described.

In testimony whereof, we affix our signatures.

KENNETH HOWIE.
WILLIAM O. TAYLOR.
